UNITED STATES PATENT OFFICE.

HENRY A. PERLMUTTER, OF BROOKLYN, NEW YORK, ASSIGNOR TO ARTISTIC BRASS & BRONZE WORKS, INC., OF NEW YORK, N. Y., A CORPORATION OF NEW YORK.

ADJUSTABLE BASE.

Application filed March 14, 1927. Serial No. 175,151.

My invention relates to adjustable bases for floor lamps, smoking stands, coffee tables and the like, and particularly to bases having an adjustable framework adapted to 5 have superimposed thereon and to have rigidly held therein a slab of onyx, marble or similar ornamental member.

In floor lamps, smoking stands, and the like, making use of such ornamental members as part of the bases thereof, it is necessary and desirable to have a framework to hold such ornamental member in place, support same above the floor and also to support the upright standard or standards of 15 the lamp, smoking stand or similar article in which such base is made use of. An object of the invention is, therefore, to provide a neat, simple, ornamental and inexpensive framework for this purpose.

Another object of the invention is to provide means on said base framework for readily adjusting same to fit the particular size and shape of the ornamental member superimposed on said framework. In practice, it 25 is very difficult to produce onyx, marble or similar ornamental substances in slabs of precisely uniform size and it is not unusual to find the slabs varying slightly in size and shape, so that where a non-adjustable base 30 framework is used, the ornamental member is not held rigidly in place, the fit is not accurate and the job as a whole is unsatisfactory. With applicant's device, however, a perfect fit is produced in every instance, 35 since the framework is accurately adjusted to the particular size and shape of the slab held therein, and it is possible to form integral with the legs of the framework laterally extending ornamental fingers, which lie 40 adjacent the edges of the ornamental slab and serve as clamping members to hold the slab rigidly in place, as well as serving for additional ornamentation. This feature has hitherto been impracticable due to the variation 45 in size and shape of the slabs used, the expense of machining, etc.

Other objects and features of the invention will appear from the following description and drawing illustrating an embodiment 50 of the invention, merely for the purpose of affording an understanding of the invention and not for limitation thereof.

In said drawing, Fig. 1 is a perspective view of an adjustable base of my invention, 55 adapted for a smoking stand, floor lamp and

the like. Fig. 2 is a cross-sectional view of part of the base, showing the mode of attachment of the leg members to the base frame, and Fig. 3 is a cross-sectional view on the line 3-3, Fig. 2.

The device comprises a spider frame or plate 10, having radial extensions or arms 12, 12 and leg members 14, 14 adjustably attached to said arms 12, the device being supported a short distance above the floor by downward extensions 16, 16 on leg members 14, 14. A slab of onyx, marble or similar ornamental member 18, indicated in dotted lines in Fig. 1, is adapted to be superimposed on the device and be rigidly held in place thereon between the upward extensions or fingers 20, 20 on leg members 14, 14.

To accommodate the device to ornamental members of varying sizes and shapes, means are provided for making the leg members 14 adjustable with respect to the arms 12. Said arms 12 are provided in their upper surfaces with grooves or channels 22, preferably taper-sided, extending longitudinally thereof, and in said channels 22 and extending in the same direction therewith are elongated slots 24. The leg members 14 are provided on their under sides with longitudinal ribs or tongues 26, also preferably taper-sided, adapted to register with and slide in the channels 22 of arms 12. In this way there is obviated the possibility of side-play between the leg members 14 and the arms 12, and there is a tight fit of the one in the other in any adjusted position. Any fastening means, such as screws 28, may be passed through the apertures 30 provided in the leg members 14, and through the elongated slots 24 in the arms 12, to hold the two together in any adjusted position. To provide greater 95 adjustability between the leg members 14 and the arms 12, additional apertures may be provided in the leg members 14, such as 31, 31.

Plate 10 is provided with a tapped aperture 32 in its center, to receive the upright standard of the floor lamp, smoking stand or other article of which the base forms a part, which upright standard passes through an aperture in the center of the ornamental member 18, and is screwed into said aperture 32.

The arms 12 on plate 10 may be of any size or shape, and although four such arms are shown in Fig. 1, it is to be understood 110

that a greater or lesser number may be used, if desired, depending on the size and shape of the ornamental member adapted to be superimposed on the device, and depending 5 also on the ornamental effects desired to be obtained.

The upwardly extending fingers 20 on the leg members 14, which lie closely adjacent the edges of the ornamental member 18 and serve to hold same rigidly in place on the device, may be of any desirable ornamental design and may be of any size or shape required to harmonize with the ornamental member 18 and with other parts 10 of the article of which the base forms a part.

To assemble the base, the leg members 14 are loosely screwed to the arms 12 of the plate 10. The slab 18 is placed on the 20 framework 10 and the leg members 14 drawn up closely against the edges of slab 18 so that the upwardly extending fingers 20 of the leg members 14 tightly clamp the slab 18, and then the screws 28 are tightened. The base when so assembled makes 25 a perfect fit and presents a pleasant appearance, and there is no play of any kind between the parts.

In one-piece base frames now in common 30 use, it is necessary to gild or plate the entire device, although but a few small parts are visible to the eye when the base is actually assembled on an article, such as a floor lamp, smoking stand or the like. With applicant's device, however, there is a substantial saving in this direction, since the only parts of the base framework visible to the eye being a few small parts of the leg members, it is only necessary to plate or 35 gild the leg members 14.

With applicant's construction, the parts can be made in a simple casting operation much quicker and at substantially lower prices as compared to base framework constructions now in common use. The device is easy to assemble and take down, it 40 has the desired adjustability to enable each

article turned out to be accurately assembled and fitted, and all the ornamental slabs can be made use of without any waste, regardless of slight variations in size or shape, and the device enables a higher degree of ornamentation to be secured.

Changes and modifications may be resorted to within the scope of my claims, 55 without departing from my invention.

I claim:

1. A base frame of the class described, comprising a central plate provided with radially extending arms having longitudinally extending grooves at their upper sides and provided with elongated slots extending therethrough at the base of said grooves, and a plurality of leg members having 60 tongues on their under sides to engage said grooves, and fastening means extending through said elongated slots to engage said legs and clamp same in adjusted relation with respect to said arms.

2. A base frame of the class described, 70 comprising a central plate provided with radially extending arms provided with longitudinally extending grooves with inclined walls opening along the upper sides of the arms and with elongated slots formed 75 in the bottom wall of said grooves, legs provided with longitudinally extending tongues with inclined walls adapted to be slidably received in said grooves, fastening members extending through said slots and engaging said legs to hold and clamp same rigidly in adjusted position with respect to said arms, and upward and downward extensions on the leg members, the latter serving as feet to support the frame and members carried thereby and the former serving to engage a block or other member supported upon the leg members and to clamp same in place when the leg members 80 are forced inwardly toward the central 85 plate and fastened in such relation.

In testimony whereof I have signed my name hereto.

HENRY A. PERLMUTTER.
